MODULAR DISPLAY STAND

Kenneth Kuenster, New Haven, Conn., assignor to
Hammermill Paper Company, Erie, Pa.

Filed Aug. 26, 1970, Ser. No. 24,707

Term of patent 14 years

Int. Cl. D6—06

U.S. Cl. D80—9

FIG. 1.

FIG. 2.

FIG. 3.

FIG. 4.

FIG. 1 is a perspective view of a modular display stand embodying my novel design;

FIG. 2 is a rear elevational view thereof;

FIG. 3 is a top plan view thereof; and

FIG. 4 is an exploded, perspective view of the top, one shelf unit and base of my modular display stand.

I claim:

The ornamental design for a modular display stand, as shown,
